UNITED STATES PATENT OFFICE.

WILLIAM MAURER AND HERMAN A. MAURER, OF ROCKLYN, WASHINGTON.

BEET-TOP CUTTER.

1,039,161.

Specification of Letters Patent. Patented Sept. 24, 1912.

Application filed April 4, 1912. Serial No. 688,547.

To all whom it may concern:

Be it known that we, WILLIAM MAURER and HERMAN A. MAURER, citizens of the United States, residing at Rocklyn, in the County of Lincoln and State of Washington, have invented certain new and useful Improvements in Beet-Top Cutters; and we do hereby declare the following to be a full, clear, and exact description of the invention, such as will enable others skilled in the art to which it appertains to make and use the same.

This invention relates to harvesters and it relates more particularly to a beet top cutter, but it may be used for harvesting plants other than beets.

An object of the invention is to provide a machine of this character for operating a band-saw having a portion traveling in horizontal relation, whereby the beet tops may be severed.

A further object of the invention is to provide means associated with the band-saw, for raising and lowering the same to the proper position for cutting the respective beet tops at the proper place; that is, immediately above the beet root.

A still further object of the invention is to provide means for properly and automatically tensioning the band-saw.

A further object is to provide a device of this character, which is so simple of construction and operation that an unskilled person may operate the same.

Further objects and advantages may appear in the following and in the claims.

In the accompanying drawings, which form a part of this application, Figure 1 is a side elevation of the machine embodying my invention, and, Fig. 2 is a front elevation thereof.

Referring to these drawings, in which similar reference characters correspond with similar parts throughout the several views, the main frame 5 is supported by a main axle 6, the latter being supported and adapted to be rotated by ground wheels 7, when the machine is drawn, through the medium of the draft-beam 8, by any proper means.

A pair of hangers 9 are carried by the main frame and support a pair of pulleys 10, which carry a band-saw 11. The frame 5 is also provided with a pair of guides 12 which engage the grooves 13 of the saw adjusting frame 14, the latter carrying an upper and a lower pair of tension pulleys

15. The upper pulleys have their axes movably seated relative to the frame 14, and are provided with spring adjusting means consisting of a plunger 16 and a spring 17, 60 so related to the upper adjusting pulleys as to hold them firmly against the band-saw at all times, and thereby to compensate for any stretch or yielding of the band-saw and thereby retain the proper tension thereof. 65 A hand lever 18 is pivotally secured to a segmental member 19 and is adapted to be adjusted relative thereto, in a well known manner. The frame 14 is connected to said hand lever 18 by means of vertical links 19, 70 a bell crank 20 and a horizontal link 21; so that, when the lever 18 is manipulated the frame 14 is thereby raised or lowered. When thus raised or lowered, the frame 14 slides through the guides 12 and carries the intermediary portions of the band-saw therewith, while the axes of the pulleys 10 remain stationary; so that, when the frame is at its uppermost position, the upper portion of the saw will assume a curved formation, while the lower part of the saw will assume a straight formation. Therefore, the saw remains under control of the springs 17, whether in upper, lower or intermediate position.

One of the pulleys 10 is provided with a stub axle 22 which connects with a shaft 23, through the medium of the knuckle joint 24, and said shaft carries a gear wheel 25, which meshes with a gear wheel 26, carried 90 by the axle 6; so that, when the axle 6 rotates the shafts 22 and 23 are rotated and carry the pulleys 10 and band-saw 11. The pulleys 10 and wheels 15 may be flanged, as shown, for preventing the saw from being forced back and off of their peripheries, and as an additional safeguard, we provide 95 a saw guide 27, of the usual construction, which may be placed as shown in Fig. 2 or in any other convenient and operative 100 position.

We have provided a driver's seat 28, carried by a spring support 29, secured at the rear end of the tongue member 8, which extends to the rear end of the main frame, 105 and it will be seen that the weight of the driver in the seat will tend to counterbalance the weight of the saw-frame and other elements connected therewith, thereby relieving a considerable amount of the 110 weight which would otherwise be burdensome to the draft animals.

It will be seen that we have provided a beet harvesting machine which is capable of attaining the foregoing objects, and which may be properly adjusted and manipulated for cutting the beet tops properly, whether the proper cutting point thereof is adjacent to the ground or a considerable distance thereabove.

We do not limit our invention to the exact 10 details of construction, combination and arrangement of parts herewith described and illustrated, but our invention may only be limited by a reasonable interpretation of the following claims.

15 We claim:

1. In a beet top harvester, a main frame, an axle supporting the frame, ground wheels supporting and adapted to rotate the axle, an adjusting frame carried in a plane for 20 ward of the ground wheels, a pair of pulleys having their axes fixed on the main frame and in the plane of the adjusting frame, a band-saw carried by the pulleys, and means associated with the main frame and with the 25 adjusting frame whereby the latter may be moved vertically for adjusting the position of the saw independently of the pulleys which carry the saw.

2. In a beet top harvester, a main frame, 30 a main axle supporting the main frame and supported by a pair of ground wheels and rotatable with the ground wheels, bearings supported by the forward end of the main frame, pulleys carried by the bearings, 35 means connecting the main axle with one of the pulleys for rotating the latter, a band-saw carried by the pulleys, and combined adjusting and tension means for the band-saw,

said means consisting of the vertically movable frame carrying wheels in contact with the saw, certain of said wheels being automatically adjustable relative to the adjusting frame.

3. In a beet top harvester, a main frame, a main axle supporting the frame and supported by a pair of ground wheels and adapted to be rotated thereby, a pair of pulleys having their axes secured to the main frame and adapted to be rotated by the main axle, a band-saw carried by the pulleys, and means for raising and lowering the operating part of the band-saw.

4. In a beet top harvester, a main frame, a band-saw supported by the main frame and adapted to travel in a vertical plane, vertical guides carried by the frame, and adjusting means associated with the guides, whereby the operating portion of the saw may be raised and lowered relative to the main frame.

5. In a beet top harvester, a main frame, a band-saw carried by the main frame, means associated with the band-saw for guiding the same, an adjusting frame for the band-saw, an adjusting lever, and means comprising a bell-crank and links for moving the adjusting means and thereby adjusting the saw.

In testimony whereof we have signed our names to this specification in the presence of two subscribing witnesses.

WILLIAM MAURER,
HERMAN A. MAURER.
